UNITED STATES PATENT OFFICE

ROBERT J. BEATTY, OF COLUMBUS, OHIO, ASSIGNOR TO THE FEDERAL GLASS COMPANY, OF COLUMBUS, OHIO, A CORPORATION OF OHIO

METHOD AND APPARATUS FOR COMPLETING PRESSED BLOWN WARE OR BLOWN WARE

Original application filed September 20, 1927, Serial No. 220,674. Divided and this application filed November 21, 1927. Serial No. 234,782.

My invention relates to a method and apparatus for completing pressed blown ware or blown ware. It has to do, primarily, with the treatment of the blown blank which results in the conversion of this blown blank into the finished article.

This is a division of my application for Letters Patent, Serial No. 220,674, filed September 20, 1927.

10. In the past, the usual method of treating the blown blank to convert it into the finished article has consisted in passing it through a lehr and then subjecting it to a series of operations by relatively independent 15 units which are each manually fed with the articles in progressive stages. Usually, there is a device fed manually for severing the cap from the blown article which frequently takes the form of a means for rotating the blown 20 blank in contact with a thin cracking flame at the desired point of severance. After the cap falls off, the tumbler is manually introduced into a grinder which grinds the edges thereof. Then, the ware is manually fed to a melting 25 or glazing machine. After this, it is manually fed to a lehr to minimize the strains set up in the melting and glazing apparatus. It is obvious that, in this process, there is a very great amount of handling of the article with 30 a consequent high labor cost.

Other processes have been devised in an effort to decrease the number of necessary operations but these have been attended by comparatively slight success. In one of these 35 operations, the usual flame crack-off device has been replaced by an acetylene or hydrogen crack-off apparatus which is semiautomatic but which must be manipulated by an operator. This device is supposed to render grinding of the edges of the tumbler unnecessary, but, in practice, a large percentage of the articles must be reground.

My invention is aimed at the development 45 of a process which will entirely eliminate the necessity for manual intervention during the crack-off of the tops and the fire polishing of the ware and which will, at the same time, reduce the steps of operation. Furthermore, my aim is to rearrange these steps of

operation in such a way as to produce a superior product with less loss from breakage.

In one form, my invention contemplates the taking of the blown blanks as they leave a conventional lehr through which they are fed for a period of time and under such conditions that the strain set up in the making will be removed therefrom. After the articles are taken from the conventional lehr, I transfer them, either manually or automatically, to a conveyer unit which automatically conveys the blown blank to a flame crack-off and rotates these blanks in a proper position while passing them under subjection to a row or rows of flames which form a part of this flame crack-off. As they emerge from the flame crack-off, the caps which have been severed from the blanks are preferably blown therefrom automatically; or these tops may be supported during the severing action by means provided, and may be removed either during or immediately after passing through the severing unit.

After leaving the severing unit, the blanks, with the caps removed, are conveyed automatically upon the same conveying unit to and through a glazing and melting unit. After leaving this glazing and melting unit upon the conveyer, they may be transferred to a second lehr which may be of the same type as the first lehr and which serves the purpose of removing the strains set up in the articles in their passage through the glazing and melting unit.

The apparatus which I preferably use in performing my process is shown in the accompanying drawings wherein similar characters of reference designate corresponding parts and wherein:

Figure 1 is a perspective view of my flame crack-off and melting and glazing apparatus embodying the conveying unit for conducting the blanks to and through them.

Figure 2 is a perspective view, partly broken away, of my flame crack-off unit.

Figure 3 is an end view, partly in section, of the device shown in Figure 2.

Figure 4 is a sectional view showing the air finger which I preferably utilize for blowing the several caps from the blanks.

Figure 5 is a modified form of device for removing the severed caps from the blanks.

Figure 6 is a detailed view illustrating the supporting wires of the device and the fingers 5 which project into the cap opening and move them along the supporting wires.

In the drawings, the preferred embodiment of my invention is shown in Figure 1 as comprising an endless chain conveyer 1 10 that is driven by a sprocket 2 and passes around the sprockets 3, 4 and 5. It receives the blown blanks, that have been taken from a conventional lehr, at station A and conducts them in the direction of the arrows to a flame 15 crack-off unit 6. It will be noted that the crack-off unit 6 is located some distance from the point where the blanks are taken from a lehr and placed on the conveyer 1, namely, at station A. The space on the conveyer 1 20 between station A and the crack-off unit 6 is termed the cooling zone and is necessary in that the blank must be sufficiently cool when it arrives at the crack-off station so that the crack-off flame may set up the necessary cracking strain. It conducts these blown 25 blanks through this crack-off unit 6, which may be covered if desired, under subjection to burner crack-off members which will be hereafter described in detail. Mechanism is 30 provided, as will also be described, for causing rotation of these blanks while under subjection to the crack-off flame.

After leaving the crack-off unit 6, these blanks with the severed caps thereon pass into 35 subjection to a finger of air which blows each cap into a waste chute 7. If desired, means may be provided, between the end of the crack-off unit, from which the glass articles emerge, and the finger of air for chilling the 40 glass articles at the line at which the tops are severed therefrom, to insure positive removal of the tops from the article.

After the blanks, with the caps removed, have passed beyond the air finger, they pass 45 into and through a glazing and melting unit 8. This glazing and melting unit may be of any suitable form. It serves to glaze and fire polish the glassware and melts and smooths the top edges of the article.

50 After the articles leave the glazing and melting unit, they are preferably removed at or near station B and may be sent through an annealing lehr. This annealing lehr may be substantially the same as the annealing lehr 55 through which the articles pass before being subjected to the crack-off and glazing and melting action. It serves to remove the strains which have been set up in the articles in their passage through the glazing and 60 melting unit and in other ways.

The crack-off unit may vary as to form but the detailed construction of the form which I have shown is disclosed best in Figures 2 and 3 and is substantially as follows:

65 Such crack-off unit consists of a frame 9,

made in two parts, connected together at their lower ends and so formed as to have an opening 10 between the upper edges thereof when the frame parts are in assembled relation. Each part of the frame is provided with angle iron ways 11 upon which travel the 70 coaster bearings 12, that are rigidly mounted upon the spindles 13. One part of the frame 9 carries a rack 14. The spindles 13 are rotatable in bushings 15 that are driven or otherwise inserted into the joints between the links of the conveyer chain 1, and these bushings form a bearing surface for such spindles.

A pinion gear 16 is rigidly mounted upon the lower end of each pinion in such position as to mesh with the rack 14 and rotate the spindle. Mounted upon each spindle immediately above the joints made in connecting the links and immediately below the cup 17, which is rigidly mounted upon the extreme 85 upper end of each spindle, is a spool 18. The spool 18 makes a sufficiently tight fit with the opening 10 in the frame 9 to prevent lateral movement or wobbling of the spindle as it passes through the cutting unit.

Horizontal supports 19 support the burners 20, which burners are made of any suitable material, and these horizontal supports have the threaded rods 21 rigidly attached thereto and depending downwardly therefrom. 95 These threaded rods extend through the castings or plates 22 in the manner shown in Figure 3. Nuts 23 on the threaded rods hold the supports 19 in the position necessary to obtain the proper level of the nozzles 24 that 100 are disposed in a horizontal row along the inner spaces of the burners 20.

Guides 25 disposed on each side of the castings or plates 22 prevent lateral or vertical movement of the castings or plates while 105 permitting horizontal longitudinal adjustment of the same. Such horizontal longitudinal adjustment is controlled by means of the screw bolts 26 that are threaded into the castings or plates 22 as shown in Figure 3. The outer ends of the screw bolts 26 are provided with collars 27 and 28 which are so disposed on the screw bolts as to embrace the plates 29, rigidly attached to the frame 9, when the screw bolts are disposed 110 in slots therein. Such construction permits rotation of the screw bolts but prevents horizontal longitudinal movement of such bolts, therefore, permits in and out adjustment of the castings or plates 22 and the burners 115 supported thereby. Such adjustment will move the nozzles 24 towards and away from the tumblers or similar glass articles carried by the conveyer.

The burners 20 are made up of a double 120 row of burner castings, one row on each side of the line of travel of the tumblers or similar glass articles, and each casting is equipped with a row of burner nozzles 24 as hereinbefore described. Also, a small baffle 30 is 125

preferably provided in each of the burner castings to distribute the incoming gases evenly throughout the interior of the burner casting. Each row of burner castings preferably consists of a plurality of such castings that are preferably the same as to length, placed end to end on one of the supports 19 and each separate burner casting is preferably independent of the others as far as fuel control is concerned. However, it will be understood that each row of burner castings may consist of any desired number of burner castings and these may be dependent upon each other in the matter of fuel control if such construction is desired.

The air finger cap remover is best shown in Figure 4 of the drawings and is constructed as follows: A tripping mechanism is mounted upon a vertical support 31 and such tripping mechanism is preferably made adjustable as to vertical position on this support. The tripping mechanism preferably comprises a tripping arm 32 that is fulcrumed to an arm 33 as at 34. The outer end of the 25 tripping arm is so positioned that it will contact with the spindles 13 on the conveyer 1 and the opposite end of this tripping arm is attached to a valve stem 35 which forms a part of the valve 36. When the tripping 30 arm 32 contacts with the spindle 13 and is moved forwardly, the valve 36 will be pulled open and constant air under pressure will be permitted to flow through the pipe 37 past the valve 36 and through the pipe 38 to contact with the severed top of the tumbler or similar glass article in the conveyer. As clearly shown in Figure 4, the constant air under pressure striking the tops of the tumblers or similar glass articles at the 35 necked portion thereof will blow these tops into the chute 7 or some other receptacle in the manner shown in this figure. As also shown in Figure 4, the constant air pipe 38 passes through or is pivotally attached to a block 39, which block is adjustable on the vertical support 31 so as to bring the pipe 38 to the height required to blow the tops from the glass articles of various sizes and into the chute 7 or other receptacle. The angle at which the air strikes the caps may be regulated by moving the pipe 38 about its pivotal attaching point 38'.

In order that the burner elements 20 may be adjusted to exactly the proper height with respect to the articles being conveyed through the cutting unit, I have provided graduated scales 40 which are rigidly attached to the castings or plates 22 and extend perpendicularly upward therefrom. As is clearly shown in Figure 2 of the drawings, the burner elements 20 may be adjusted so that the nozzles 24 will impinge a flame at exactly that line on the glass articles at which the top is to be cracked off. This is accomplished by raising or lowering the supports 19 until the lugs 41

on the burner supports 19 register at the same heights on the graduated scales 40. Graduated scales may be provided as an integral part of the mechanism governing the horizontal longitudinal movement of the castings 70 or plates 22 with the burner elements 20 thereon.

A wire and finger cap remover may be used by me as a substitute for the air finger cap remover if desired. This device is best shown in Figures 5 and 6 of the drawings and is preferably constructed in the following manner:

An endless belt 42, made of some suitable material, passing around pulley wheels 43 and 44, has wire fingers 45 mounted thereon at spaced intervals as shown in Figure 5. These wire fingers 45 are preferably straight and are adapted to pass along a path substantially in the center of a conveyer track which is 80 made up of two wires 46 and 47 supported in some well-known manner above the tumblers or similar glass articles on the endless chain conveyer. Such conveyer track is preferably inclined upwardly as shown in Fig. 90

In the operation of this device, the conveyer track, made up of wires 46 and 47, is disposed beneath the top edges of the caps of the tumblers or similar glass articles as 95 shown in Figure 6. As the tops are severed in the passage of the blanks through the cutting unit they are prevented from falling and are then lifted from the glass articles by the upwardly extending conveyer track. At 100 substantially the same time that the tumblers or similar glass articles enter the cutting unit the wire fingers 45 traveling on the conveyer belt 42 enter the tops of the articles as shown in Figure 5. After they are lifted entirely 105 away from the body of the tumbler or similar glass articles the tops may be carried to a chute or other receptacle by the wire conveyer track or may be removed from the conveyer track by hand.

The term "crack-off unit" may be understood as defining a unit of any suitable form in which a series of flames, hot enough to set up a cracking strain along a selected line but not hot enough to melt the glass, are used.

Having thus described my invention, what I claim is:

1. The method of completing ware of the type described which comprises severing the caps from the blanks and then blowing the 120 caps off of such blank.

2. The method of completing ware of the type described which comprises severing the caps from the blanks, and removing these caps from the blanks by air under pressure.

3. The method of completing ware of the type described which comprises severing the caps from the blanks, removing these caps by air under pressure, and then passing the blanks through a melter.

4. Apparatus for removing the tops from articles of glassware comprising a means for severing the tops from said articles and means for removing the tops therefrom, said last named means embodying a jet of air.

5. Apparatus for removing the tops from articles of glassware having necks thereon comprising a means for severing tops from said articles and means for removing said severed tops from the articles of glassware, said means comprising means for directing a jet of air against the necks of said tops to blow such tops from the articles.

6. Apparatus for removing the tops from articles of glassware comprising a means for severing the tops from said articles and means for removing the tops therefrom, said last-named means embodying an intermittently operated jet of air.

7. Apparatus for removing the tops from articles of glassware comprising a means for severing the tops from said articles and means for removing the tops therefrom, said last-named means embodying an upwardly inclined jet of air.

8. The method of completing glassware comprising placing a hot blank on a conveyer at a predetermined distance from the crack-off station to allow for cooling thereof, severing the top from such blank, removing the said severed top by air under pressure, and then conveying said blank through a melter.

9. The method of completing ware of the type described which comprises severing the cap from a blank by a crack-off heat, blowing the severed cap off such blank, and then passing said blank through a melting unit.

10. Apparatus for removing the tops from articles of glassware comprising a conveyer having a means for severing the tops from said glass articles, and a positive fluid cap removing means in association therewith.

11. Apparatus for completing glassware comprising an endless conveyer, means for severing the tops from articles of glassware, said means embodying burner elements disposed on opposite sides of the path of travel of said articles of glassware, and means adjacent said burner elements for removing said severed tops, said last-named means comprising air under pressure.

12. Apparatus for removing the tops from articles of glassware comprising an endless conveyer, a crack-off unit for severing tops, means comprising a jet of air under pressure for removing said severed tops, and a melting unit.

13. Apparatus for completing glassware comprising an endless conveyer having cup-shaped article holders, a flame crack-off unit, a fluid cap removing means and a melter.

14. Apparatus for completing articles of glassware comprising a continuously moving, one level, article conveyer, a flame crack-

off unit, a fluid cap removing means and a melter.

15. The method of finishing an article of glassware which comprises cracking off the cap therefrom by a flame crack-off, removing the cracked-off cap by air under pressure, and fire polishing the severed edge of said article of glassware while continuously conveying said article of glassware without stoppage during the entire finishing process.

16. The method of completing ware of the type described which comprises conveying the blanks bodily through a crack-off flame in substantially upright position while simultaneously rotating said blanks and blowing the cracked off caps from said blanks.

17. Apparatus for removing excess material from glass blanks comprising an endless conveyor, a series of blank supporting members on said conveyor, means for impinging each one of a series of pin points of flame upon each blank at the line at which the cracking off is desired as they are transported by said conveyor, said pin points of flame being spaced so as to effect an alternate heating and cooling of the blanks along the cracking-off line, means for rotating said blanks as they are transported under subjection to the said series of spaced pin points of flame, and means for blowing off the cracked off portion from said blanks as they are carried onwardly by said conveyor.

18. Apparatus for removing excess material from glass blanks comprising an endless conveyor, a series of blank supporting members on said conveyor, means for impinging each one of a series of pin points of flame upon each blank at the line at which cracking off is desired as they are transported by said conveyor, said pin points of flame being spaced so as to effect an alternate heating and cooling of the blank along the cracking off line, means for rotating said blanks as they are transported under subjection to the said series of spaced pin points of flame, means for blowing off the cracked-off portion from said blanks as they are carried onwardly by said conveyor, and means for finishing the edges of said blanks by applying flames thereto while the blanks continue in their course of travel.

In testimony whereof I hereby affix my signature.

ROBERT J. BEATTY.
